UNITED STATES PATENT OFFICE.

VERNER M. GAY, OF DANBURY, CONNECTICUT.

FOLDABLE TABLE.

1,308,350.

Specification of Letters Patent. Patented July 1, 1919.

Application filed April 30, 1918. Serial No. 231,716.

To all whom it may concern:

Be it known that I, VERNER M. GAY, a citizen of the United States, residing at Danbury, in the county of Fairfield, State 5 of Connecticut, have invented certain new and useful Improvements in Foldable Tables; and I do hereby declare the following to be a full, clear, and exact description of the invention, such as will enable others 10 skilled in the art to which it appertains to make and use the same.

The present invention relates to new and useful improvements in collapsible table structures, more particularly of that type 15 including outer table top sections hingedly connected with a central section, whereby they may swing downwardly from the edges of the central section to afford a table surface having only the area of said central 20 section, or may extend in the plane of the central section to afford an enlarged table surface.

It is in general the object of the present invention to simplify the structure of devices of this character and to increase the ease with which such devices may be manipulated to assume the various desired 25 relations of their parts, and to assure a proper firmness and rigidity of the parts in their 30 various positions.

In this connection it is more particularly an object to provide a means connecting all of the outward table top sections which are hinged to the central table top section, 35 whereby said outer sections are simultaneously movable to raised and lowered position and may be held in raised position by a single common supporting member.

A further object resides in the provision 40 of a foldable table of the present nature whose maximum and minimum table top surfaces may be respectively round and square in contour, in contradistinction to collapsible tables wherein adjustment of the 45 table surface must in one instance procure a decided oblong shape of the table surface.

That operation of the table may be especially facilitated, it is an especial object to provide a structure including an arrangement of folding parts such that these parts 50 will not interfere with each other as they are folded, and to accomplish this without the use of fasteners for holding any of the folding parts in folded position.

With the above and other objects and

advantages in view, the invention resides more particularly in the novel combination, formation and arrangement of parts hereinafter described and particularly pointed out in the appended claim.

60

In the accompanying drawings:

Figure 1 is a side elevational view of the improved table, with all of its table top sections in extended position.

Fig. 2 is a plan view of the table as arranged in Fig. 1.

Fig. 3 is a side elevational view of the table, with its outer table top sections folded downwardly to afford a minimum table top surface.

Fig. 4 is a fragmentary bottom perspective view of the table top showing the means for holding the triangular table top sections in raised position at their edge portions remote from the hinged edges 70 thereof.

Fig. 5 is a fragmentary sectional view on the line 5—5 of Fig. 3.

Fig. 6 is an enlarged detail sectional view taken vertically through the leg of the table 80 and showing the means for holding the common supporting collar of the outer table top sections.

Referring now more particularly to the drawings, the present embodiment of the invention includes a single post or leg 5 for supporting the table top structure, which is provided at its lower end with a foot plate or base 6 from the peripheral portion of which braces 7 extend in upwardly convergent relation to an intermediate portion of the leg, to insure sufficient strength and stability of the supporting leg. Rigidly secured to the upper end of the leg 5 is a central table top 8 which is square in contour 90 and of sufficiently large dimension to discharge the usual supporting function of an ordinary table of small size.

Secured by hinges 9 to each outer edge of the top section 6 is an extension section 11 100 of substantially square shape and substantially equal in size to the top section 8, one side edge of the extension top section 11 being flush with the adjacent parallel edge of the top section 8, and its other side edge being offset inwardly of the corresponding parallel side edge of the top section 8. The degree of offset of the sections 11 is substantially equal to the individual thickness or supplemental top sections 13, one of which 110

is secured to the inwardly offset edge of each section 11 by hinges 12. These sections 13 are substantially triangular and their outer sides are curved to form, when extended 5 with the sections 11, continuations of the outer edges of said sections 11, which are correspondingly curved whereby the increased table top area formed by the extension sections is circular in contour. To hold 10 the adjacent otherwise free edges of the extension sections 11 and 13 against relative downward movement, plates 14 are pivoted to the under surfaces of the sections 13 adjacent their free edges and may be swung to 15 engage the under surfaces of the sections 13, thereby affording a positive support for the free inner edges of the sections 13 and aiding also in holding the entire series of extension sections in raised position by reason 20 of the intersecting arcs of downward folding movement of the sections. The major supporting means of the sections in raised position comprises bars 15 hinged to the outer edge portions of the under surfaces of 25 the sections 11 and hinged to a collar 16 which is slidably mounted on the leg 5. To hold the collar in raised position on the leg, a pair of pawls 17 is mounted in diametrically opposed recesses 18 in the leg and are 30 resiliently urged outwardly of the periphery of the leg by a spring 19 extending transversely therethrough and bearing against said walls, retraction of the pawls into the recesses permitting passage of the collar 35 therewith.

The operation of the table to procure its various desired positions is thus very simple and easily effected. In folding the table, the plates 14 are swung to retracted position 40 permitting the sections 13 to drop. The pawls 17 are then retracted, permitting the collar 16 to move downwardly on the shaft, and the table sections 11 to fold downwardly. By reason of the inward offsetting 45 of the hinge carrying side edges of the sections 11, the sections 13, while extending at right angles to the sections 11, lie out of position to interfere with the folding of the adjacent sections 11, and extend inwardly of

and parallel with the inner faces of the adjacent sections 11. All of the extension sections in folded position thus lie vertically at the sides of the central top section 6, to afford a structure convenient in its use and attractive in appearance. To utilize the 50 maximum table top surface of the device, it is merely necessary to grasp two of the sections 11 and swing them outwardly and upwardly until the collar 16 is raised above the pawl 17, and then to raise the top sections 13 which depend from the sections 11 and are thus within easy reach, and secure them by the pivot plates 14, it being observed that if desired, one of these sections 13 may remain in lowered position to provide an 55 inset space in the table top surface which may be desirable for performing various types of work on the table.

While I have described the central table top section as being square, it may comprise 60 any preferably equilateral figure, although a square shape of the central section and a substantially square and equal shape of the extension sections hinged directly thereto 65 permit a most convenient folding.

What is claimed is:

A foldable table including a supporting means, a central table top section rigidly secured to said supporting means, table top sections hinged to the edges of the central 70 table top section, each hinged section having one side flush with the adjacent parallel side of the central section and its other side inwardly offset from the corresponding other side of the central section, a table top section 75 hinged to each inwardly offset side and means for holding the table top sections in extended position, the offset of the second mentioned sections being such as to permit the third mentioned sections to lie wholly 80 beneath the central sections when the hinged sections are folded.

In testimony whereof, I affix my signature, in the presence of two witnesses.

VERNER M. GAY.
